UNITED STATES PATENT OFFICE.

WARREN H. TAYLOR, OF STAMFORD, CONNECTICUT, ASSIGNOR TO THE YALE & TOWNE MANUFACTURING COMPANY, OF STAMFORD, CONNECTICUT.

LEVER-ARM FOR DOOR CHECKS AND CLOSERS.

SPECIFICATION forming part of Letters Patent No. 729,697, dated June 2, 1903.

Application filed March 19, 1903. Serial No. 148,576. (No model.)

To all whom it may concern:

Be it known that I, WARREN H. TAYLOR, of Stamford, in the county of Fairfield and State of Connecticut, have invented certain new and useful Improvements in Lever-Arms for Door Checks and Closers; and I do hereby declare the following to be a full, clear, and exact description of the invention, such as will enable others skilled in the art to which it applies to make and use the same.

My invention relates to an improvement in lever-arms for door checks and closers, and while it is designed particularly for use in connection with liquid door checks and closers, it may be used with any construction wherein a pawl-and-ratchet connection is employed between the lever-arm and spring.

The object of the invention is to provide a reversible lever-arm with a vertically-sliding pawl constructed to fall by gravity and always depend below the arm in a position to engage the teeth of the ratchet-wheel; and it consists in the details of construction and combination of parts, as will be more fully described, and pointed out in the claims.

In the accompanying drawings, Figure 1 is a view in vertical section, showing a door-check with my improvement applied thereto. Fig. 2 is a view in longitudinal section of the lever-arm and pawl. Fig. 3 is a plan view of same. Fig. 4 is a view in transverse section, and Fig. 5 is a view in perspective of the pawl.

1 represents a horizontal cylindrical casing closed at its ends and provided on its top with a cylindrical chamber 2 and with lips 3, having screw-holes therein for the attachment of the device to a door. The shaft or spindle 4 and the spring 5 are located within the chamber 2, the shaft extending out through the top of said chamber and also through its bottom into horizontal chamber 1, the bearing for the shaft between the two chambers being packed to prevent the passage of oil or liquid up into the spring-chamber 2.

The crank 6 is secured to the lower end of shaft 4 and is connected by pitman 7 with the piston or other checking-surface 8, the latter preferably having one or more valved open-

ings 9 therein, through which the liquid within chamber 1 may freely pass when the piston 8 is moving toward the shaft 4 and which closes when the piston is moving away from the shaft, as in the act of closing the door.

The piston normally or when the door to which the piston is attached is closed rests beyond or in front of the by-pass valve 10, and until this position of the piston is reached the liquid in front of the piston has a more or less restricted avenue of escape through the by-pass valve. After the piston passes the by-pass the movement of the piston is retarded by the liquid confined in front of the piston and which can escape only by leakage around the piston.

The shaft 4 passes up through chamber 2 and is provided with a crescent-shaped upper end to fit within a correspondingly-shaped opening in the inner end of the lever-arm 14. Located within the spring-chamber 2 and loosely surrounding shaft 4 is the ratchet-sleeve 13. This sleeve is either directly or indirectly connected to the inner end of the spring 5 and connects the latter to the shaft, so that when the shaft 4 is turned by the opening of the door the spring will be wound up or compressed, and when the door is released the spring will then unwind or expand and operate to close the door.

The lever-arm 14, as before stated, is secured on the upper end of shaft 4, and the free end of the jointed section thereof is secured to the door-frame in the usual manner. The lever-arm is provided at its inner end with an elongated slot 15 for the reception of the rectangular plate or pawl 16, which latter engages the teeth 17 of the ratchet-sleeve 13 and locks the sleeve and its connected spring and the lever-arm together. The pawl 16 is of greater width than the thickness of the lever-arm through which it passes, and the slot in said arm is of such size as to permit free vertical movement of the pawl without any lateral movement. The pawl is provided on one side, and preferably near its center, with a vertical rib 18, which latter fits within a corresponding groove in the arm and absolutely prevents any tilting movement of

the pawl. The rib 18 projects on opposite sides of the arm and is bent laterally at its ends, so as to overlap the arm and prevent the withdrawal or displacement of the pawl.

5 With this construction it will be seen that the pawl has at all times a bearing throughout its entire length against the walls of the slot, and, as it is not pivoted, the pressure of the teeth 17 against the free end thereof does 10 not tend to raise the pawl. The pawl being free to fall by gravity always depends below the lever. Hence when the lever is turned over or its position reversed the pawl simply shifts its position accordingly.

15 When it is desired to increase or decrease the tension of the spring, the pawl may be lifted out of engagement with the teeth 17 until the proper adjustment has been reached and then permitted to fall back into engagement with the teeth.

It is evident that changes in the form and construction of the several parts might be resorted to without departing from the spirit and scope of my invention, and hence I would 25 have it understood that I do not confine myself to the details herein shown and described, but consider myself at liberty to make such changes as fairly fall within the spirit and scope of my invention.

30 Having fully described my invention, what

I claim as new, and desire to secure by Letters Patent, is—

1. In a door-closer, a lever-arm having an elongated slot, a vertically - sliding pawl mounted in the slot, and means for preventing vertical displacement of the pawl. 35

2. In a door-closer, a lever-arm having an elongated slot therein, and a vertically-sliding pawl of greater width than the thickness of the arm and provided on its edges with 40 projections overlapping the arm for preventing displacement of the pawl.

3. In a door-closer, a lever-arm having an elongated slot and a groove opening into said slot and a vertically-sliding pawl mounted in 45 the slot and having a rib resting in the groove.

4. In a door-closer, a lever-arm having an elongated slot and a groove opening into said slot, and a vertically-sliding pawl mounted in the slot and having a rib resting in the groove, 50 and also provided with projecting lips overlapping the wall of the slot for preventing the displacement of the pawl.

In testimony whereof I have signed this specification in the presence of two subscribers. 55

WARREN H. TAYLOR.
